UNITED STATES PATENT OFFICE.

CATHARINE S. SUNDGREN, OF NEW YORK, N. Y., ASSIGNOR TO PHILIP A. CONNE, OF NEW YORK, N. Y.

LETTER-SHEET.

SPECIFICATION forming part of Letters Patent No. 791,731, dated June 6, 1905.

Application filed November 23, 1904. Serial No. 233,952.

To all whom it may concern:

Be it known that I, CATHARINE S. SUNDGREN, a citizen of the United States, and a resident of the borough of Brooklyn, in the city and State of New York, have invented a new and useful Improvement in Letter-Sheets, of which the following is a specification.

The object of my invention is to provide a letter-sheet in which a communication—such, 10 for instance, as an invoice or bill—may be sent sealed and stamped from one party to a second party, from the second party back to the first party after the letter-sheet has been opened and examined, and finally from the 15 first party back to the second party after the letter-sheet has been again opened and examined.

A further object is to provide a letter-sheet 20 of the above character in which inclosures may be safely carried without danger of being unintentionally removed therefrom.

In the accompanying drawings, Figure 1 represents a front face view of the letter-sheet unfolded. Fig. 2 is a back face view of the 25 same. Figs. 3, 4, and 5 are respectively front face, back face, and cross-sectional views of the letter-sheet when folded for its first transmission. Figs. 6, 7, and 8 are similar views of the letter-sheet when folded for its second 30 transmission with a separate inclosure therein. Figs. 9, 10, and 11 are similar views of the letter-sheet when folded for its third transmission, and Fig. 12 is a front face view of the letter-sheet unfolded as it appears after all 35 of its securing-flaps have been removed.

The letter-sheet comprises a plurality of folding sections. In the present instance four of such folding sections are shown, (denoted, respectively, by 1, 2, 3, and 4.) Three of these 40 folding sections have gummed side flaps for purpose of sealing the letter-sheet in its folded arrangement. In the present instance the two end sections 1 and 4 and the intermediate section 2 are provided, respectively, with side 45 flaps 5, 6, and 7. The back faces of the side flaps 5 of the section 1 are gummed, and the front faces of the side flaps 6 and 7 are gummed. The front face of the end section 1 is arranged to receive an address—as, for instance, the ad-

dress of the second party, viz., the party to 50 which the letter-sheet is intended to be first transmitted. The back face of the section 2 is arranged to receive the address of the first party—viz., the party who originally transmits the letter-sheet and to whom the letter-sheet is to be returned by the second party. 55 The back face of the section 4 is also arranged to receive the address of the second party for use in transmitting the letter-sheet to the second party after it has been returned to the 60 first party. The three sections which are arranged to receive the addresses may also be provided with postage-stamps where the letter-sheet is intended for use in transmittal through the mails. 65

The front faces of the letter-sheet other than upon the section 1 are arranged to have a communication indorsed thereon—as, for instance, an invoice or bill. In the present instance the letter-sheet is shown as being arranged for the 70 indorsement thereon of an itemized bill.

In practice the letter-sheet is used as follows: The first party, or sender of the letter-sheet, folds the sections together, as shown in Fig. 5, with the side flaps 6 and 7 folded inwardly, leaving the front face of the section 1 exposed, which front face is arranged to receive the address of the second party, to whom the letter-sheet is to be transmitted. The flaps 5 are folded back over the side edges 75 of the several sections and secured to the back of the folded letter-sheet. When the second party receives the letter-sheet, he proceeds to open the same by cutting the flaps 5 from the section 1. This permits the letter-sheet to be 80 unfolded. The second party may then fold a check or other payment-voucher or communication within the letter-sheet, leaving the back face of the section 2 exposed, the folds of the sections being as shown in Fig. 8. This 85 back face of the section 2 is the one which is arranged to receive the address of the first party. The side flaps 7 of the section 2 are then folded over the side edges of the sections and secured to the back of the folded letter-sheet. When the first party receives the letter-sheet, he may proceed to cut the flaps 7 90 from the section 2. This permits the letter- 95

- sheet to be unfolded, and the first party may then remove the contents of the letter-sheet, and if it is a bill he may receipt the bill and again fold the letter-sheet, as shown in Fig. 5 11, leaving the back face of the section 4 exposed, which back face is arranged to receive the address of the second party. The flaps 6 may then be folded over the side edges of the sections and secured to the back of the folded letter-sheet. The second party upon receipt of the letter-sheet may open the same by cutting the flaps 6 from their section 4. The letter-sheet will then have the appearance shown in Fig. 12 and may be filed away by 15 the second party for future reference.
- It is to be understood that I do not wish to limit myself to the number of folding sections herein shown, as it is obvious that a greater or lesser number of folding sections may be 20 employed, the gist of the invention lying in the provision of side flaps upon those three of the folding sections a face of each one of which can be brought into an exposed position when the letter-sheet is folded without 25 exposing the contents of the letter-sheet.

What I claim is—

1. A letter-sheet having a plurality of folding sections, three of the sections having gummed side flaps and arranged to receive addresses.
2. A letter-sheet having a plurality of folding sections, three of the sections having gummed side flaps, certain faces of said three

sections being arranged to receive addresses and stamps thereon.

35

3. A letter-sheet having a plurality of folding sections, three of the sections having gummed side flaps, one of the said sections being arranged to receive an address on its front face and the other two sections being 40 arranged to receive addresses on their back faces.

4. A letter-sheet having a plurality of folding sections, the two end sections and an intermediate section adjacent to one end section 45 having gummed side flaps, the said three sections being arranged to receive addresses thereon.

5. A letter-sheet having a plurality of folding sections, an intermediate section and one 50 end section having side flaps gummed on their front faces and the other section having side flaps gummed on their back faces, the said first-named two sections being arranged to receive addresses on their back faces and the 55 last-named section being arranged to receive an address on its front face.

In testimony that I claim the foregoing as my invention I have signed my name, in presence of two witnesses, this 18th day of November, 1904.

CATHARINE S. SUNDGREN.
